HUMLESS ELECTRODYNAMIC PICKUP

Donald F. Balmer, New Haven, Conn., assignor to
 The Soundscriber Corporation, New Haven,
 Conn., a corporation of Connecticut

Application August 8, 1944, Serial No. 548,583

6 Claims. (Cl. 179—100.41)

1

This invention relates to phonographs, and more particularly to an electrodynamic moving coil pickup especially adapted for use on flat disk records having means to eliminate hum or other disturbances produced by stray magnetic fields in the vicinity thereof.

One object is to provide an improved moving coil pickup of the above nature in which said coil is completely filled with a solid iron core which is movable with said coil and reduces the air gap between the poles of the surrounding magnetic frame and consequently increases the sensitivity of the device and the strength of the amplified signals.

A further object is to provide a pickup of the above nature having an auxiliary adjustable "hum-bucking" coil located adjacent the regular moving coil to compensate for the effects of neighboring stray magnetic fields from the turntable motor, transformers, etc.

A further object is to provide a pickup unit of the above nature in which the hum-bucking coil will be located in a stationary position on one side of the moving coil of the pickup unit.

A further object is to provide a pickup of the above nature employing means to reduce the effects of undesired vertical oscillations of the pickup stylus and thereby avoid resultant "gurgling" sounds which might otherwise occur.

A further object is to provide an improved pickup for use on disk records and the like which will be inexpensive to manufacture, simple in construction, compact, ornamental in appearance, low in inertia, and very efficient and durable in use.

With these and other objects in view, which will appear as the description proceeds, there has been illustrated on the accompanying drawings one form in which the invention may conveniently be embodied in practice.

In the drawings:

Fig. 1 is a side view of a "hum-bucking" pickup unit embodying the present invention.

Fig. 2 is a top plan view of the same.

Fig. 3 is a front view of the same.

Fig. 4 is a transverse sectional view of the same taken along the line 4—4 of Fig. 2, looking in the direction of the arrows.

Fig. 5 is a transverse sectional view of the same, taken along the line 5—5 of Fig. 2, looking in the direction of the arrows.

Fig. 6 is a longitudinal sectional view of the front portion of the pickup unit, taken along the line 6—6 of Fig. 2, looking in the direction of the arrows.

2

Fig. 7 is a perspective view of the rear cushioning support for the pickup unit.

Fig. 8 is a perspective view of the front cushioning support for the pickup unit.

5 Fig. 9 is a diagrammatic view of the forward part of the pickup unit frame and moving coil showing in dotted lines the theoretical horizontal axis about which the pickup armature would oscillate undesirably unless such oscillation is suppressed.

10 Fig. 10 is a diagrammatic view of the same showing the inclined horizontal axis about which the moving coil of an actual pickup manufactured by mass production would usually oscillate and produce "gurgling" effects unless suppressed.

15 Fig. 11 is a diagrammatic view of the electrodynamic pickup frame, moving coil, and the inclined stationary "hum-bucking" coil mounted on the side of the frame, showing how the hum-producing effect of a stray magnetic field from the turntable motor is substantially neutralized.

20 The present invention is an improvement over a Patent No. 2,213,936, granted to Lincoln Thompson on Sept. 3, 1940, entitled "Electrodynamic pickup."

25 Referring now to the drawings in which like reference numerals denote corresponding parts throughout the several views, the numeral 10 indicates a solid rectangular permanent magnet 30 block embraced by a pair of Z-shaped magnetic frame members 11, 12 having inwardly offset parallel pole pieces 13, 14. The rear portions of the frame members 11, 12 are clamped tightly against the magnet block 10 by means of a pair of clamping screws 15, 16.

35 The inwardly offset pole pieces 13, 14 are adapted to embrace a laterally vibrating pickup armature A comprising an elongated light rigid frame 29 preferably made of plastic material such as 40 "Lucite." The armature A carries a small moving elongated coil 37 mounted on a vertical axis and spaced from said poles 13, 14 by air gaps 17, 18.

The forward ends of the pole pieces 13, 14 have 45 two pairs of bifurcated extremities 19, 20, each pair having mounted therein a yieldable transverse rectangular Neoprene front cushioning armature support 21 having a central square aperture 22 fitted about a square end lug 30 of said armature A.

The rear of the armature A is supported by means of an elongated yieldable transverse Neoprene rear cushion member 23 having a pair of rearwardly extending lugs 24, 25 on its ends, said 50 lugs being provided with cylindrical screw-en-

gaging recesses 26, 27 which tightly embrace the screw rod 16.

The intermediate portion of the rear cushion member 23 is provided with a horizontal central slit 28 which is adapted to receive a thin reduced rear horizontal end lug 31 on the Lucite frame 29 (see Fig. 5).

The numeral 32 indicates a cylindrical stylus rod which is adapted to be vibrated laterally by the groove 35 of a disk record 34, said stylus rod being preferably provided with a conical sapphire tip 33 (see Figs. 5 and 6). The disk record 34 is preferably made of molded plastic material such as "Vinylite," and is adapted to have the spiral groove 35 indented therein by means of a recording machine such as was disclosed in the Reissue Patent No. 22,183, issued to Lincoln Thompson, on Sept. 22, 1942, and entitled "Apparatus for recording sound on thin disks."

The numeral 38 indicates a central iron core, about which is wound a moving coil 37, said core being movable with said coil 37 and filling the entire space therein without air gaps.

The Lucite frame 29 has an intermediate upwardly opening recess 36, a thin rear vertical section 39, and a thick forward vertical section 40, the combined moving coil 37 and core 38 being tightly cemented between the sections 39, 40 of said Lucite frame 29, as best shown in Fig. 6.

Provision is also made of a rectangular top flat fibre strip 41 cemented to the top of the pole pieces 13, 14 and having an inclined side section 42 upon which is mounted an elongated "hum-bucking" coil 43, the inclination of which may be adjusted manually by bending said side section 42 with respect to the strip 41 until the hum produced by the lines of force of a stray magnetic field S. F. emanating from a turntable motor 43a (Fig. 11) or other source of electrical disturbances has been compensated for. The hum-bucking coil 43 is provided with a central iron core 44 similar to the core 38.

It will be understood from the above construction that by placing the stationary hum-bucking coil 43 in close proximity to the driven moving pickup coil 37 in such a position that both coils will be affected by the same disturbing stray fields it will only be necessary to connect the coils in opposition so as to substantially eliminate all hum and other undesired disturbing noises.

In order to prevent undesired vertical movements of the rear of the pickup armature A, which might cause "gurgling" noises, provision is made of an elongated transverse brass wire 45 having a downwardly bowed central portion 46 which engages the rear armature cushion member 23, the ends 50, 51 of said wire 45 being rigidly secured to the frame members 11, 12 as by cement, as shown.

While the exact reason for this result is not entirely understood, the following is thought to be true: Due to the fact that the construction of the moving coil under rapid mass production methods is not always perfectly symmetrical, vertical movements of the rear of the pickup armature, if permitted, would generate voltages in the moving coil 37 which would not be equal in all directions, as in Fig. 9, but would be unbalanced since the axis of such vertical motion would be inclined as indicated in an exaggerated manner by the line 48 in Fig. 10. This would result in the production of "gurgling" noises unless the vertical movements of the rear of the pickup armature were suppressed.

An additional function of the bent wire 45 is

that it tends to maintain the central slit 28 of the rear cushion member 23 closed about the rear lug 31 at all times. This will prevent erratic rocking movements of the armature which might otherwise be produced by the vertical movements of the pickup armature.

It will be understood that the wire 45, however, offers an interference with the normal lateral vibrations of the pickup stylus.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In an electrodynamic pickup for reproducing sounds from the grooves of a phonograph record, a rectangular permanent magnet block, a pair of Z-shaped magnetic frame members clamped upon opposite faces of said block, said frame members having a pair of closely spaced inwardly offset pole pieces, a moving armature located in the air gap between said pole pieces and carrying a pickup coil, a stylus rigidly connected to said armature, yieldable cushions for the front and rear of said armature, and means secured to said frame to engage the cushion at the rear of said armature to restrain the latter from vertical movement whereby substantially any tendency to produce "gurgling" will be prevented.

2. In an electrodynamic pickup for reproducing sounds from the grooves of a phonograph record, a rectangular permanent magnet block, a pair of Z-shaped magnetic frame members clamped upon opposite faces of said block, said frame members having a pair of closely spaced inwardly offset pole pieces, a light weight elongated rigid moving armature resiliently supported at its ends in a pair of soft rubber pads carried by said magnetic frame members at the front and rear thereof, and means mounted in said frame to engage the rear pad to restrain the rear of said armature from vertical movement whereby substantially any tendency to produce "gurgling" will be prevented.

3. In an electrodynamic pickup for reproducing sounds from the groove of a phonograph record, a rectangular permanent magnet block, a pair of magnetic frame members embracing said block, said frame members having a pair of closely spaced inwardly offset pole pieces, a pick-up-carrying moving armature located in the air gap between said pole pieces, a stylus connected with said armature, a yieldable cushion mounted in said frame members for resiliently receiving the forward portion of said armature to permit it to vibrate with said stylus, and a curved wire member for holding the rear of said armature to prevent vertical movements thereof and thus preventing any tendency to produce "gurgling."

4. In an electrodynamic pickup for reproducing sounds from the grooves of a phonograph record, a rectangular permanent magnet block, a pair of Z-shaped magnetic frame members clamped upon opposite faces of said block, said frame members having a pair of closely spaced inwardly offset pole pieces, a pickup coil carrying 70 moving armature located in the air gap between

said pole pieces, a stylus connected with said armature, and a curved brass wire member secured to the outer portions of said frame members for holding the rear of said armature from undesired vertical movements.

5. In an electrodynamic pickup for reproducing sounds recorded in a laterally undulated groove of a phonograph record, a magnetic frame having a pair of pole pieces separated by an air gap, a pickup armature located in said air gap and carrying a stylus which rides in said groove and is vibrated laterally thereby, and additional means secured to said frame to restrain the rear of said pickup armature from undesirable vertical vibrations around axes at right angles to the axis of its lateral stylus vibrations whereby any tendency to produce "gurgling" will be prevented.

6. In an electrodynamic pickup for reproducing sounds from a laterally undulated groove of a phonograph record, a magnetic frame having a pair of poles separated by an air gap, a pickup carrying movable armature located in said air gap, a yieldable rear cushion member mounted

in said frame, said cushion member having a slit for resiliently embracing the rear of said armature, and means to press downwardly upon the top of said cushion to hold said slit closed to prevent erratic movements of the rear of said armature.
